UNITED STATES PATENT OFFICE.

ROBERT BRUCE, OF WELLINGTON, KANSAS.

HASP-FASTENER.

1,122,469.

Specification of Letters Patent. Patented Dec. 29, 1914.

Application filed September 15, 1914. Serial No. 861,853.

To all whom it may concern:

Be it known that I, ROBERT BRUCE, a citizen of the United States, residing at Wellington, in the county of Sumner and State 5 of Kansas, have invented a new and useful Hasp-Fastener, of which the following is a specification.

The present invention relates to improvements in hasp fasteners, the same being a 10 perfected form of the hasp fastener shown in my U. S. Letters Patent, No. 1,079,390, granted to me November 25, 1913, one object of the present invention being the provision of a novel construction for the mounting of the key, whereby the same is always 15 disposed in ready position for insertion within the hasp to lock the same and receive the usual locking means for the same.

A further object of the present invention, 20 is to simplify the construction of the hasp fastener above referred to, thus making the same less expensive to manufacture and more practical and efficient in use.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed can be made within the scope of what is claimed without departing from the spirit of the invention.

35 In the drawings—Figure 1 is a view in elevation of a car door with my improved hasp fastener operably secured thereto. Fig. 2 is a perspective view of the hasp fastener. Fig. 3 is a sectional view taken on line 3—3 40 of Fig. 2. Fig. 4 is a perspective view of the key *per se*. Fig. 5 is a section taken on line 5—5 of Fig. 3.

Referring to the drawings, the numeral 4 designates the hasp which is provided with 45 a slot 5 extending therethrough and adjacent one of the edges thereof is a raised shoulder 6, the latter being provided with an opening 7 extending transversely therethrough. The remote end of the hasp is 50 provided with an aperture 8 extending therethrough for the reception of a securing staple 9 as clearly shown in Fig. 1.

Rigidly secured to the car wall is a base plate 10 provided with a lug 11 that projects therefrom and which lug is provided

with an aperture 12 disposed transversely therethrough, and an aperture 13 formed at right angles to the first mentioned aperture or longitudinally through the lug. The lug 11 is of such a size that it passes freely 60 and at the same time snugly through the slot or opening 5 of the hasp. The base 10 is provided with the aperture 14 extending therethrough, which aperture provides means whereby the base plate may be rigidly secured to the wall of the car or other supporting structure.

Attached to the base plate above the lug 11 are the two parallel walls 15, which support the pin 16 adapted to fit in the elongated slot 17 of the key 18, said key being so disposed that it will slide between the walls 15 and be normally guided therein, in a vertical position so that its reduced end 19 will be projected into and out of the 75 aperture or opening 13. The lower end of the slot 17 is enlarged as at 20 so that when the parts are in the position as shown in Figs. 2 and 3, the enlarged end 20 will aline with the openings 7 and 12 so that a pad 80 lock or seal 21 may be passed therethrough as illustrated in Fig. 1. It will thus be seen that the key 18 is always disposed in ready position for operation, either for withdrawal from the lug 11 or for insertion 85 therein, the same when fully extended upwardly assuming the dotted line position as shown in Fig. 2, the end 18 engaging the rear wall of the supporting member thereof adjacent the base plate 10 so that the key 90 may be supported in elevated position without being entirely reversed, the end 19 always being downward. It will thus be seen that with this structure, that the objection to the key therein shown which is attached 95 to the base plate by a chain, is overcome, the key being thus disposed always in proper position for the introduction therein or the removal therefrom.

What is claimed is:

The combination with a hasp having an opening through the body, and with a lug projecting at right angles therefrom and provided with an aperture, of a base plate provided with a lug, said lug being provided with an aperture adapted to aline with the aperture of the lug of the hasp to receive a locking member, said lug further being provided with an aperture at right angles thereto, a pair of plates carried by 100 105

the base plate, a pin mounted in said plates, a key provided with a longitudinal slot mounted upon the pin for guidance between the plates, the free end of the pin being disposed for registration with the longitudinal opening of the lug, the lower end of the said slot of the key being enlarged for registration with the apertures of the shoulder of the hasp and of the lug to permit of

the insertion therethrough of the locking member.

In testimony that I claim the foregoing as my own, I have hereto affixed my signature in the presence of two witnesses.

ROBERT BRUCE.
